J Nock
Inkstand

No 10.310

Patented Dec 13 1853.

UNITED STATES PATENT OFFICE.

JOSEPH NOCK, OF PHILADELPHIA, PENNSYLVANIA.

HINGE FOR INKSTAND-COVERS.

Specification of Letters Patent No. 10,810, dated December 13, 1853.

To all whom it may concern:

Be it known that I, JOSEPH NOCK, of the city and county of Philadelphia and State of Pennsylvania, have invented a new and 5 useful Inkstand and Ink-Well Cover; and I do hereby declare that the following is a full and exact description thereof, reference being had to the accompanying drawings and to the letters of reference marked 10 thereon.

The nature of my invention consists in providing the ink stand or ink well cover with a curvilinear hinge on the top of the ink stand or ink well cover, which cover 15 is to be closed to form a round or smooth turned face, and gives an opportunity of cleaning when soiled, inside as well as outside. And can be used by any scholars, in the public schools, or any other places, 20 where writing ink is to be used, as it is the most convenient in opening and shutting, and of course keeps the ink clean and saves the ink from evaporating when shut. And the manner of which I construct the hinge 25 is, with one solid part, as the moving lid, (figure "a") and the other part is hollow, being cast or stamped of sheet brass or other material (figure "b") forming, when put together and shut, a regular round hinge, 30 and is flat on the bottom, and can be applied on any flat surface, desk, table, or ink stand; the only difference is, that, it is to be screwed on wood, but cemented on glass,

iron, stone, or other hard substances, those that are cemented do not require as broad a 35 rim, as those on wood, and also the bottom rim inside requires to be broad, in order to hold the ink-well of glass. But, I change the inside of the bottom part, in order to get a better hold, for the cementing on 40 hard substances, by bending it downward, or otherwise. This hinge is constructed like any other hinge, with the exception only, that the pin is laid in the hollow part, from the under side, and with soft solder both 45 ends of the pin is soldered fast, and the solid moving lid has the hole for the pin or axis of the hinge drilled through the hinge part, as shown in the pattern correctly.

What I claim as my invention, and desire to secure by Letters Patent, is—

The application of the stamped round part, and the solid part, (or the moving lid, or cover) fitted together as a hinge, which forms a rounded smooth turned face, and 55 the manner in which the pin is connected with both parts, as herein described, using for that purpose the aforesaid "two pieces to form a regular curvilinear or round turned hinge," made of any materials which 60 will produce the intended effect.

JOSEPH NOCK.
